INSERT HUB FOR A RIBBON SPOOL

Robert P. Buhram and Richard D. Hensley, Farmersville, Ohio, assignors to Columbia-Great Lakes Corp., Dayton, Ohio

Filed Feb. 20, 1970, Ser. No. 21,536

Term of patent 14 years

Int. Cl. D8—99

U.S. Cl. D8—220

FIG-1

FIG-2

FIG-3

FIG-4

FIG-5

FIG. 1 is a perspective view of an insert hub for a ribbon spool showing our new design;

FIG. 2 is another perspective view thereof;

FIG. 3 is one end view thereof;

FIG. 4 is the opposite end view thereof; and

FIG. 5 is a side view thereof.

We claim:

The ornamental design for an insert hub for a ribbon spool, substantially as shown.
